(57) **CLAIM**

The ornamental design for a hand crank and mains rechargeable LED flashlight, as shown.

DESCRIPTION

FIG. 1 is a front view showing my new design.

FIG. 2 is a rear view thereof.

FIG. 3 is a side end view thereof.

FIG. 4 is other side view thereof.

FIG. 5 is a plan view thereof.

FIG. 6 is an underneath view thereof.

FIG. 7 is a front isometric view thereof.

FIG. 8 is a rear isometric view thereof.

FIG. 9 is a rear isometric view with crack handle showing; and,

FIG. 10 is a front isometric view with electric plug showing.

The surface(s) or portion(s) of the article not shown in the drawing or described in the specification form(s) no part of the claimed design.
